CLOCK RADIO

John Y. Sugihara, Streamwood, Ill., assignor to
Gemini International Corp.

Filed Dec. 28, 1970, Ser. No. 26,672

Term of patent 14 years

Int. Cl. D10—01

U.S. Cl. D42—7

FIG. 1

FIG. 2

FIG. 3

FIG. 4

FIG. 5

FIG. 1 is a perspective view of a clock radio showing my new design;

FIG. 2 is a top plan view thereof;

FIG. 3 is a front elevational view thereof;

FIG. 4 is a side elevational view thereof; and

FIG. 5 is a rear elevational view thereof.

The portion of the drawing in dotted lines is for illustrative purposes only.

I claim:

The ornamental design for a clock radio, as shown and described.
